AUXILIARY MAILBOX FLAG

Edwin C. Esten, Lima, Ohio

Application October 26, 1949, Serial No. 123,569

3 Claims. (Cl. 232—34)

1

This invention relates to signals or flags used on rural mail boxes for indicating that mail has been deposited in the box, and in particular an auxiliary flag attached to the usual mail box flag which snaps to an outwardly extended position to facilitate indicating the presence of mail in the box from a point on the longitudinal axis of the box.

The purpose of this invention is to improve the visibility of a mail box flag whereby the position of the flag may readily be observed from the side or end of the box.

The usual mail box flag is nested against the flat side of the mail box when the mail box is empty and when mail is placed therein the flag is actuated to a vertical position to indicate the presence of mail therein. The flag, being mounted against the side of the box, remains parallel to the side of the box and it is, therefore, difficult to determine the position of the signal from a point on a plane parallel to the longitudinal center of the box. With this thought in mind this invention contemplates an auxiliary flag mounted in combination with the usual flag and adapted to snap to an outwardly extended position when released as the usual signal or flag is actuated to an upwardly extended position to indicate the presence of mail in the box.

The object of this invention is, therefore, to provide means for mounting an auxiliary flag on the staff of the usual mail box flag whereby the auxiliary flag is parallel to the usual flag when the mail box is empty and positioned at right angles to the usual flag when the mail box contains mail.

Another object of the invention is to provide an auxiliary mail box flag which extends outwardly to indicate the presence of mail in the box that may be attached to the usual mail box flag staff.

A further object of the invention is to provide an auxiliary signal flag for rural mail boxes that is adapted to extend at right angles to the usual flag, which is of a simple and economical construction.

With these and other objects and advantages in view the invention embodies an auxiliary mail box flag pivotally mounted by a pin in a bracket adapted to be attached to the usual mail box flag staff, and a spring for retaining the auxiliary flag in a position parallel to the usual flag and also for holding the auxiliary flag in an outwardly extended position.

Other features and advantages of the invention will appear from the following description

55

2

taken in connection with the drawings wherein:

Figure 1 is a view showing an end of a mail box with the auxiliary flag attached to the usual signal flag staff in full lines and also indicating the position of the auxiliary and usual flag in dotted lines before the auxiliary flag has been moved to an outwardly extended position, the rear portion of the mail box being broken away.

Figure 2 is a view similar to that shown in Figure 1 showing the signal flag in the upwardly extended position showing that mail is in the mail box and with the auxiliary flag extended outwardly.

Figure 3 is a plan view of the auxiliary flag attachment illustrating the position of the auxiliary flag with the parts latched.

Figure 4 is a side elevational view of the signal flag taken on line 4—4 of Figure 3 with the auxiliary flag in a latched position and with parts broken away.

Figure 5 is a sectional plan taken on line 5—5 of Figure 4 also showing the parts in a latched position.

Figure 6 is a detail showing the upper corners of the flag with parts broken away and illustrating the auxiliary flag in the unlatched position.

Figure 7 is a plan view similar to that shown in Figure 3 and showing the auxiliary flag in the unlatched position similar to that shown in Figure 6.

Figure 8 is a similar detail showing the auxiliary flag moved through an angle of 90°, to the indicating position.

Figure 9 is a detail illustrating the bracket for attaching the auxiliary flag to the usual flag staff.

Figure 10 is a similar detail illustrating the inner end of the auxiliary flag with the outer part of the flag broken away.

Figure 11 is a detail illustrating a modification wherein the auxiliary flag is pivotally mounted in the attachment on a stationary pin with slots provided in the mounting hub of the auxiliary flag.

Figure 12 is an elevational view similar to that shown in Figure 4 showing the type of mounting illustrated in Figure 11 with the parts in the latched position and with parts broken away and shown in section.

Figure 13 is an end elevational view of the type of mounting shown in Figures 11 and 12.

Figure 14 is a detail showing a plan view of the inner end or hub of the auxiliary flag shown in Figures 11 and 12.

Figure 15 is a similar view showing the opening

through a flange of the mounting bracket of the attachment shown in Figures 11 and 12 and with the auxiliary flag shown in section.

Referring now to the drawings wherein like reference characters denote corresponding parts the auxiliary mail box signal of this invention includes a panel or flag 10, a mounting bracket 11, a pin 12 and a spring 13.

The flag 10 is formed with a flat panel having hubs 14 and 15 on the inner end with notches 16 and 17 spaced from the hubs and with a U-shaped flange 18 extended outwardly between the hubs.

The bracket 11 is formed as illustrated in Figure 9 with outwardly extended flanges 20 and 21 which are provided with slots 22 and 23 respectively for receiving the end of the pin 12 with the pin extended through the hubs 14 and 15 of the flag 10. The bracket is also provided with lugs 24 and 25 positioned at the edges of the flanges 20 and 21 and spaced from the slots of the flanges whereby with the ends of the pin 12 in the adjacent ends of the slots the lugs register with notches 16 and 17 of the flag 10. With the parts in this position the spring 13 snaps the flag 10 outwardly to the position illustrated in Figures 2 and 8 where it is at a right angle to the usual signal flag 26. As illustrated in Figure 5, one end 27 of the spring bears against the face of the bracket 11 and the other end 28 bears against the inner face of the flange 18 of the auxiliary flag.

The bracket 11 is also provided with a short flange 29 on the inner edge, and clips 30 and 31, which extend around the staff engaged end of the flag 26, as shown in Figures 7 and 8 extend from this flange. The bracket is also provided with clips 32 and 33 that are bent around the upper and lower edges, respectively, of the flag 26, as shown.

It will be noted that with the auxiliary flag 10, as illustrated in Figure 3, the flag will be retained in a parallel position against the usual flag 26 and when it is moved as in Figure 6 it will be snapped by the spring 13 to the outwardly extended position as illustrated in Figure 2. When mail has been removed from the box the flags are moved downwardly to the position shown in full lines in Figure 1 and the auxiliary flag 10 is pressed against the flag 26 and slid back to the position illustrated in Figure 3 where it is latched by the lugs 24 and 25 whereby it will remain in this position.

In the modified form illustrated in Figures 11 to 15, inclusive, hub elements 34 and 35 of an auxiliary flag 36 are provided with slotted openings 37 and 38, respectively and a stationary pin 39 carried by flanges 40 and 41 of a bracket 42 extends through the slots. In this design the edge 43 of the flange 40 is provided with a notch 44 in which the edge 45 of the flag 36 is positioned with the auxiliary flag latched to the usual flag 46.

In this design a spring 47 is positioned on the pin 39 and with one end 48 of the spring bearing against a semi-circular flange 49 of the auxiliary flag and with the other end 50 of the spring bearing against the base of the bracket 42 the spring will snap the auxiliary flag to the extended position when the flag is slid to the unlatched position with the edge 45 removed from the notch 44. In this design the bracket 42 is provided with clips 51 similar to the clips 30 and 31 which extend around the inner end of the usual flag 46, and clips 52 corresponding to

the clips 32 and 33 that extend over the edges of the sides, respectively, of the flag 46. It will be understood, therefore, that the auxiliary flag may be attached to the usual flag with the pivot pin movable or in a stationary position, as may be desired.

As illustrated in Figures 1 and 2 the usual signal flag is carried by a staff 53 that is pivotally mounted on a pin 54 in a bracket 55 on the side of a mail box 56 having a cover 57 and the bracket 55 is provided with a projection 58 over which the staff 53 is snapped to retain the flag in the upright position.

With the parts arranged in this manner the auxiliary flag of this invention normally remains in the position illustrated in full lines in Figure 1 wherein it is parallel to the usual signal flag and as mail is deposited in the mail box and the usual flag actuated to an upright position the auxiliary flag is snapped outwardly to a position perpendicular to the usual flag, as illustrated in Figure 2, whereby the presence of mail in the box may be determined from a point parallel to the longitudinal center of the box.

It will be understood that the other modifications may be made in the design and arrangement of the parts without departing from the spirit of the invention.

What is claimed is:

1. In an auxiliary signal for a mail box having a usual flag pivotally mounted thereon, a mounting bracket attached to the staff-attached end of the flag, an auxiliary flag having a pin fixedly mounted on its corresponding end, said pin being slidably connected to said mounting bracket, latch means retaining the auxiliary flag in a position parallel to the usual flag, and means in the bracket for urging the auxiliary flag to an outwardly extended position perpendicular to the usual flag when the latch means is released.

2. In an auxiliary signal for a mail box having a usual flag pivotally mounted thereon, a mounting bracket attached to the staff-attached end of the flag, said mounting bracket having outwardly extended flanges thereon and said flanges having elongated slots therein, an auxiliary flag having a pin fixedly mounted on its corresponding end, said pin slidably mounting the auxiliary flag in the slots of the said mounting bracket, latch means retaining the auxiliary flag in a position parallel to the usual flag, and means in the bracket for urging the auxiliary flag to an outwardly extended position perpendicular to the usual flag when the latch means is released.

3. In an auxiliary signal for a mail box having a usual flag pivotally mounted thereon, a mounting bracket attached to the end of the flag, an auxiliary flag, a pin mounting the corresponding end of the auxiliary flag on the bracket, said pin being slidably connected to one of said parts and fixedly connected to the other of said parts, latch means for retaining the auxiliary flag in a position parallel to the usual flag, and means in the bracket for urging the auxiliary flag to an outwardly extended position perpendicular to the usual flag when the latch means is released.

EDWIN C. ESTEN.
